Primary Examiner — Cathron Brooks*Assistant Examiner* — Clesce Moore, Jr.(74) *Attorney, Agent, or Firm* — Nixon & Vanderhye, P.C.(57) **CLAIM**

The ornamental design for "television set," as shown and described.

DESCRIPTION

FIG. 1 is a top, left perspective view of a television set in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines shown illustrate portions of the television set that form no part of the claimed design.
